UNITED STATES PATENT OFFICE.

LUTHER L. KNOX, OF BELLEVUE, PENNSYLVANIA, ASSIGNOR TO BLAW-KNOX COMPANY, OF PITTSBURGH, PENNSYLVANIA, A CORPORATION OF NEW JERSEY.

FURNACE-DOOR FRAME AND THE LIKE.

1,232,864.

Specification of Letters Patent. Patented Oct. 29, 1918.

Application filed April 3, 1918. Serial No. 226,403.

To all whom it may concern:

Be it known that I, LUTHER L. KNOX, a resident of Bellevue, in the county of Allegheny and State of Pennsylvania, have invented a new and useful Improvement in Furnace-Door Frames and the like, of which the following is a full, clear, and exact description, reference being had to the accompanying drawings, forming part of this specification, in which:

Figure 1 is a front elevation of a door frame embodying my invention.

Figs. 2 and 3 are sections on the line II—II and III—III, respectively, and

Fig. 4 is a section of a portion of the structure illustrating the manner of assembling the parts.

My invention has relation to furnace door frames, or other hollow sheet metal structures, in which the parts composing the structure are united by welding.

The object of my invention is to provide a structure of this character having a novel interior bracing and reinforcing system of the character which will avoid forming perforations in the plates or sheets forming the structure and which is of a character to give the structure a considerable degree of flexibility or elasticity.

A further object of my invention is to provide a structure of this character in which the welds between the parts may be advantageously located, while, at the same time, permitting the use of the peculiar bracing and reinforcing system which I prefer to employ.

The nature of my invention will be best understood by reference to the accompanying drawings in which I have shown it applied to a furnace door frame, and which will now be described, it being premised, however, that various changes can be made in the details of construction and arrangement of the parts, without departing from the spirit and scope of my invention; as defined in the appended claims.

The body of the structure shown in this drawing is formed from an inner metal plate or sheet 2 and the outer plate or sheet 3. The lateral edge portions of the plate or sheet 2 are bent outwardly as shown at 2^a to form the side walls of the structure. The arched door opening 4, open at its bottom, is formed in both plates or sheets, the opening 55 being larger in the plate or sheet 3 than it is

in the plate or sheet 2. The edge portions 5 of the sheet 2 surrounding the opening 4 are bent outwardly to form the walls of said opening, and the extreme edge portions are again bent away from said opening into the plane of the sheet 3 to form the welding flange 6. These flanges meet and are adapted to be welded to the edge wall of the plate 3 around said opening 4, as indicated at 7. In this manner the weld between the parts 65 adjacent to the door opening is located at some distance from the opening in the manner and for the purpose more fully described in my Patent No. 1,191,519 of July 8, 1916.

The plate 3 is outwardly offset at each of 70 its edges to form the door-guiding projections 8 and is welded not only to the flange 6 in the manner just described, but also to the edges of the lateral flanges 2^a of the plate 2. The upper portion of the plate 2 is bent 75 horizontally inward to form the top wall of the structure, being welded to the upper end of the plate 2, and is also extended to form the attaching and lifting flange 9.

Secured to one of the said members, in the 80 present instance to the member 2, are a plurality of internal projections 10, formed each with a slot 11. Secured to the inner surface of the other plate, are a plurality of hook projections 12, whose hook ends are adapted 85 to engage the slots 11. The two sets of projections are preferably welded to the inner surfaces of the respective plates or sheets so as to avoid any perforations therein. These projections are welded in place before the 90 inner and outer plates or sheets are assembled and welded. The plates or sheets are then brought together in the manner illustrated in Fig. 4, and by longitudinal movement of one plate or sheet with respect to the 95 other, the hooks 12 are caused to engage the slots 11 in the manner which will be readily understood by reference to Fig. 4.

These engaging projections securely tie the two members of the structure together 100 against internal strains, the slots 11 being, however, made sufficiently large to permit of some inward movement of the two members relatively to each other. This gives the structure sufficient elasticity to enable 105 it to stand the expansion and contraction strains.

It will be noted that the form of two plates or sheets is such that they can be 110 readily assembled in the manner illustrated

in Fig. 4, while, at the same time, permitting the weld 7 to be made at the desired distance from the door opening.

The structure may be provided with a 5 cooling fluid, such as water, by any suitable system of connections.

In the drawings, I have shown the supply pipe 13 having a branch extending downwardly within each side portion of the structure. The heated water rises to the top and escapes at the outlet connection 14.

I claim:

1. A hollow water sheet cooling structure comprising two metal plates or sheets, one 15 of said plates or sheets having a plurality of internal slotted projections; and the other plate or sheet having a corresponding number of hook members whose hooks extend in a direction to engage the slots of said projections by a substantially parallel movement of one of the plates or sheets with respect to the plane of the other one; substantially as described.

2. A hollow water cooled structure comprising two metal plates or sheets, one of said plates or sheets having a plurality of internal slotted projections, and the other plate or sheet having a corresponding number of hook members whose hooks extend in 30 a direction to loosely engage the slots of said projections by a substantially parallel movement of one of the plates or sheets with respect to the plane of the other one; substantially as described.

3. A hollow water sheet cooling structure formed of two metal plates or sheets, one of said plates or sheets having a plurality

of internal slotted projections, and the other plate or sheet having a corresponding number of hook members adapted to engage the slots of said projections, said members being united to each other by welded connections, the members having welding portions which are brought into welding relation to each other by a longitudinal movement of one section relatively to the other, such movement also causing the engagement of the hook members with the slots; substantially as described.

4. A hollow water cooled furnace door 50 frame, comprising two plate or sheet members composed of inner and outer plate members, each of said members having a door opening formed therein, the metal of one of said members being flanged to form the wall 55 of the door opening with its free edge portion bent in a direction away from said opening and welded to the other member, one of said members having a plurality of hooks secured to its interior surface and the other 60 member having a plurality of slotted projections engaged by said hooks, said inner and outer members having their welding edges arranged to be brought into welding relation to each other by the movement of 65 one member in a plane substantially parallel to the plane of the other member, such movement also causing the engagement of the hook members with the slots; substantially as described.

In testimony whereof I have hereunto set my hand.

LUTHER L. KNOX.
